UNITED STATES PATENT OFFICE

157,601

SHEET OF STATIONERY OR THE LIKE

Eugenie J. Jones, Webster Groves, Mo.

Application March 5, 1949, Serial No. 1,241

Term of patent 7 years

(Cl. D59—14)

To all whom it may concern:

Be it known that the undersigned, Eugenie J. Jones, a citizen of the United States, resident of Webster Groves, St. Louis County, Missouri, has invented a new, original, and ornamental Design for a Sheet of Stationery, or the like, of which the following is a specification, reference being had to the accompanying drawing, forming a part thereof.

The figure on the drawing shows a face view of a sheet of stationery, or the like, showing my new design, the essential features of which reside in the portions shown in full lines.

I claim:

The ornamental design for a sheet of stationery, or the like, substantial as shown and described.

EUGENIE J. JONES.
